James J. Chambers
his ATTORNEY.

UNITED STATES PATENT OFFICE.

NATHAN H. DAVIS, OF PHILADELPHIA, PENNSYLVANIA.

BEAM-STRUT.

No. 804,938.

Specification of Letters Patent.

Patented Nov. 21, 1905.

Application filed April 14, 1905. Serial No. 255,530.

To all whom it may concern:

Be it known that I, NATHAN H. DAVIS, a citizen of the United States of America, residing in the city and county of Philadelphia, in the State of Pennsylvania, have invented a certain new and useful Improvement in Beam-Struts, of which the following is a true and exact description, reference being had to the accompanying drawings, which form a part thereof.

My invention relates to a construction of a strut or post for truss-beams, especially such as are known as "brake-beams," the object of my invention being to provide a strut especially well adapted for its purposes in use and for being secured conveniently and firmly in its position in the beam.

The nature of my improvements will be best understood as described in connection with the drawings, in which they are illustrated, and in which—

Figure 1 is an elevation of a truss-beam embodying my improved beam-strut. Fig. 2 is a perspective view of the two parts making up the beam-strut shown in assembled position. Fig. 3 is perspective view of the main strut member, and Fig. 4 a perspective view of the separable head-section of the strut.

A indicates the compression member of the beam, which is here indicated as made up of a web A², with flanges, such as are indicated at A³.

A' is the tension member of the beam, and C is the strut or post of the beam, which according to my construction is made up of the main straight member D and the supplemental head-section E. The section D is provided with a lateral opening or socket D', which rests on the tension member, and at its other end is formed with a hook-like head (indicated at D²) and adapted to fit over the flange on one side of the compression member A. Just inside of the head D² the main strut member is cut away, forming the shoulder D³ and flat surface D⁷. As shown, a transverse groove D⁴ is formed immediately adjacent to the shoulder D³ and merges into a rib D⁵, extending up from the flat surface D⁷, while an angular transverse arm D⁶ extends

from the shoulder D³, merging into the flat surface D⁷, a hole D⁸ being formed immediately in front of this longitudinal rim and close to the head D². Hanger-lugs D⁹ are provided at the lower end of the strut, the body of which is longitudinally slotted, as indicated

at D¹⁰, for the entry of the brake-lever, a pin-hole D¹¹ being provided for a pin used in holding the brake-lever in position.

The head-section E of the strut is formed with a hooked end E², adapted to engage the flange of the compression member on the opposite side to that engaged by the head D² and with an elongated shank which is made to fit into the cut-away portion of the main strut-section, its end E³ abutting against the shoulder D³, ribs E⁴, fitting into the grooves D⁴, grooves E⁵, fitting over the rib D⁵, a longitudinal angular slot E⁶, fitting over the angular longitudinal arm D⁶, while a flat surface E⁷ is provided to fit on the surface D⁷ and a rivet-hole E⁸ at the head of the shank is formed to register with a rivet-hole D⁸.

In practice the socket D' is fitted over the tension member A' and the hooked head D² forced over the flange A³ of the compression member of the truss. The separable head-section E is then put in place on the opposite side of the compression member and against the recess formed on the end of the main strut member, the grooves and ribs of the member E being complementary to those of the main strut member, so that the two fit together and are finally secured together, as well as to the compression member of the truss, by a rivet passing through the holes D⁸ E⁸, the interengaged ribs and grooves securely locking the two sections of the strut together, preventing any relative longitudinal or lateral movement of the central section E with respect to the main section.

By forming the separable head with the elongated shank and securing it to the main section by means clamping them together near the compression member a firm union is secured, the tail of the shank acting on the rivet or other securing device preventing any rocking action.

Having now described my invention, what I claim as new, and desire to secure by Letters Patent, is—

1. A truss-beam strut or post made up of a main section formed to extend between the tension and compression members of the truss and to fit against and conform to one side of the compression member, a separate head-section formed to fit against the other side of the compression member and having an elongated shank adapted to lie in contact with the adjacent side of the main strut-section, and means for securing the head-section to the

main section situated at the head of the elongated shank and close to the compression member of the beam.

2. A truss-beam strut or post having a head formed to fit one side of the compression member of the beam and its body adjacent to said head cut down and formed with longitudinal and transverse ribs, a separable head-section formed to fit on the other side of the compression member and formed with complementary longitudinal and transverse grooves to fit in the cut-down body portion of the main strut member, and means for securing the head-section to the main strut.
- 15 3. A truss-beam strut or post having a head formed to fit one side of the compression mem-

ber of the beam and its body adjacent to said head cut down to form the shoulder D³, and face D⁷, and provided with the angular buttress-rib D⁶, springing from the shoulder and merging in the face D⁷, a transverse rib and a rivet-hole in face D⁷, and a separable head-section formed to fit on the other side of the compression member and with complementary longitudinal and transverse grooves and a rivet-hole to fit in the cut-down section of the main strut.

NATHAN H. DAVIS.
